CLAIM

The ornamental design for a vehicle wheel exterior surface, as shown and described.

DESCRIPTION

FIG. 1 is a front elevation of the vehicle wheel exterior surface in a preferred embodiment, showing our new ornamental design;

FIG. 2 is a front enlarged fragmentary perspective view thereof;

FIG. 3 is a front enlarged fragmentary perspective view thereof;

FIG. 4 is a front enlarged fragmentary perspective view thereof;

FIG. 5 is a front perspective view thereof;

FIG. 6 is a sectional view thereof taken along line 6—6 in FIG. 1;

FIG. 7 is a front elevation of a vehicle wheel exterior surface showing a second embodiment of our new ornamental design, the sole difference being in the reduced length of the spokes;

FIG. 8 is a front enlarged fragmentary perspective view thereof;

FIG. 9 is a front enlarged fragmentary perspective view thereof;

FIG. 10 is a front enlarged fragmentary perspective view thereof; and,

FIG. 11 is a front perspective view thereof.

The broken line showing of environmental structure in FIGS. 1, 3, 5, 7, 9 and 11 of the drawing is for illustrative purposes only and forms no part of the claimed design.
